UNITED STATES PATENT OFFICE.

VINCENT BENDIX, OF CHICAGO, ILLINOIS.

ENGINE-STARTER.

1,173,766.

Specification of Letters Patent. Patented Feb. 29, 1916.

Application filed April 26, 1915. Serial No. 24,029.

To all whom it may concern:

Be it known that I, VINCENT BENDIX, a citizen of the United States, residing at Chicago, in the county of Cook and State 5 of Illinois, have invented certain new and useful Improvements in Engine-Starters; of which the following is a specification.

My invention relates to a starter for an engine, more particularly a gas engine and 10 the like, characterized by the employment of a screw-shaft operated by a motor and a pinion screw-threaded upon the shaft and adapted to travel longitudinally in one direction along the shaft into engagement 15 with the rotary member of the engine to be started and to travel longitudinally in the opposite direction after being automatically thrown out of engagement with the engine member when the engine begins to 20 run on its own power.

The object of this invention is to provide a simple and efficient driving connection between the motor such as an electric motor and the screw shaft which connection is 25 characterized by being of a yielding nature and also one permitting a slight longitudinal movement of the screw shaft for a purpose hereinafter explained.

In the drawing the figure represents a 30 sectional elevation of a portion of an electric motor and the screw shaft and pinion together with the yielding driving connections constituting the main feature of this invention.

Referring to the embodiment of my invention as herein shown the prime mover is here an electric motor 1 whose armature shaft is by preference extended to form the driving shaft 2. This motor is mounted 35 within a casing 3 which also contains or encloses the transmission mechanism including the screw-shaft, pinion and yielding driving connections with the driving shaft 2, and also provides an outboard bearing 4 for 40 the outer end of the screw shaft.

The screw shaft 5 is screw-threaded as to its intermediate portion, its outer portion being mounted to rotate in a bushing 6 in the bearing 4 and its inner end being operatively connected with the armature or driving shaft 2 in the manner hereinafter explained. The pinion 7 is screw-threaded upon the screw-shaft, and is adapted to travel longitudinally thereon and also 45 rarely therewith, the same being adapted to engage some rotatable member of the en-

gine such as the circular rack 8 on the fly wheel 9 of such engine.

The armature or driving shaft 2 is secured in suitable manner as by means of the 60 key 10 to a sleeve 11 fitting upon such armature shaft and also upon the inner cylindrical end of the screw-shaft which is consequently in alinement with the armature shaft. A spring 12 which is coiled around 65 the sleeve constitutes the yielding driving connection between the driving shaft 2 and the screw-shaft and for this purpose one end of the spring is secured to the sleeve and the other to the screw-shaft. As shown the 70 inner end of the spring has a loop or eye 13 which is anchored to a stud 14 which, in the present instance, passes through the sleeve and enters the driving shaft although it is not necessary that it enter the latter 75 but only engage the sleeve. In the present instance where this stud passes into the driving shaft 2 it is not necessary that the key 10 be employed although I prefer to do so. The other or outer end of the spring terminates in a loop or eye 15 which is anchored to the stud 16 which enters the cylindrical portion of the screw shaft. This latter stud enters the screw-shaft at a point slightly in 80 advance of the outer end of the sleeve 11 85 and the adjacent ends of the driving shaft and the screw shaft are also slightly separated with the result that the screw-shaft and the sleeve are capable of telescoping action so as to permit of a slight longitudinal movement of the screw-shaft.

From the foregoing description it will be understood that the spring 12 constitutes a yielding driving connection between the motor and the screw-shaft, the driving being from the driving shaft 2 to the sleeve 11 90 thence to the spring 12 and finally to the screw-shaft.

By the provision of the yielding driving connection better starting action is obtainable particularly in that the pinion is kept in mesh with the engine member such as the fly wheel when the engine is passing over the compression points with the result that vibration of the pinion on the screw-shaft during the operation of the engine is prevented. This result is accomplished by the provision of the spring 12 which is capable of increasing the speed of the screw-shaft whenever the load of the shaft is relieved to any extent, that is when the engine has just passed over the compression point.

This action of the spring is positive and instantaneous and takes its place faster than the motor can pick up and transmit increased speed so that the variable speed of the engine has no effect upon the starting operation.

Another practical advantage obtained by my yielding driving connection is the elimination or absorption of shock at the time 10 when the pinion ceases its longitudinal travel and starts to rotate with the shaft, which time is represented by the contact between the lug 17 projecting forwardly of the pinion and the lug or stop 18 on the screw shaft. This contact is not abrupt or forcible 15 but is cushioned by reason of the yielding driving connection.

Still another practical advantage which resides in the fact that in case the teeth of 20 the pinion and rack 8 should be in alinement and thereby contact end to end, such contact will be cushioned by reason of the fact that the screw-shaft is capable of a slight yielding movement with respect to the sleeve 11 25 which movement is resisted by the spring 12.

I claim:

1. A starter for engines comprising a shaft having a screw-threaded portion and a cylindrical inner end, a driving device 30 which is screw-threaded upon the shaft and adapted to travel longitudinally thereon and to engage a part of the engine to be driven, a motor having a driving shaft in axial alinement with the shaft, a sleeve fitting 35 over the ends of both shafts, and secured to

the driving shaft, and a yielding driving connection between the sleeve and screw-shaft.

2. A starter for engines comprising a shaft having a screw-threaded portion and 40 a cylindrical inner end, a driving device which is screw-threaded upon the shaft and adapted to travel longitudinally thereon and to engage a part of the engine to be driven, a motor having a driving shaft in axial 45 alinement with the shaft, a sleeve fitting over the ends of both shafts, and secured to the driving shaft, and a spring coiled around the sleeve with its ends anchored to the sleeve and screw-shaft respectively. 50

3. A starter for engines comprising a shaft having a screw-threaded portion and a cylindrical inner end, a driving device which is screw-threaded upon the shaft and adapted to travel longitudinally thereon and 55 engage a part of the engine to be driven, a motor having a driving shaft in axial alinement with the shaft, a sleeve fitting over the ends of both shafts, and secured to the driving shaft, the adjacent ends of the 60 two shafts being normally separated to permit of a longitudinal movement of the screw-shaft within the sleeve, and a yielding driving connection between the sleeve and screw-shaft.

VINCENT BENDIX.
